(57) **CLAIM**

The ornamental design for a boat storage canopy, as shown and described.

DESCRIPTION

FIG. 1 is a perspective view of the boat storage canopy, which is the subject of the present design;

FIG. 2 is a right side elevational view thereof, the left side elevational view being a mirror image thereof;

FIG. 3 is a front elevational view thereof;

FIG. 4 is a rear elevational view thereof; and,

FIG. 5 is a top plan view thereof.

1 Claim, 2 Drawing Sheets

FIG. 4
